United States Patent Office.

WILLIAM ASPLEY ROBINSON, OF AUBURN, NEW YORK.

Letters Patent No. 86,454, dated February 2, 1869.

IMPROVEMENT IN BOLTS FOR STOVE-DOORS, &c.

The Schedule referred to in these Letters Patent and making part of the same.

To all whom it may concern:

Be it known that I, WILLIAM ASPLEY ROBINSON, late of Birmingham, England, but now in the city of Auburn, county of Cayuga, and State of New York, have invented a new and useful Improvement for the Securing of Doors to Stoves for Railway-Cars; and I do hereby declare that the following is a full, clear, and exact description of the same, reference being had to the annexed drawing, in which—

Figure 1 represents a front elevation of the stove-door, and

Figure 2, a sectional plan of fig. 1, on a line of $y-z$.

Figs. 1 and 2 represent an ordinary stove-front, A being the door, and B, the frame.

To secure the effectual closing of the door A to the frame B is this invention, which consists of a draw-bolt, C, having a knuckle-jointed end, D, secured to the door A, by means of the casing E.

To open the door, the knuckle-jointed end D of the draw-bolt C requires to be placed in a line with the bolt, as shown by the dotted line L, and by means of

the handle H, the bolt C can be drawn towards the stop-lug J, which prevents the bolt C from being drawn back further than necessary to clear the keeper K, on the frame B.

To secure the door after closing it, the draw-bolt C is simply moved forward, until the knuckle-end D falls at right angles with the bolt C, which cannot be again withdrawn until the knuckle-end D is placed in position.

Having thus fully described my invention, What I claim therein as new, and desire to secure by Letters Patent, is—

The draw-bolt C, having a knuckle-jointed end, D, in combination with the keeper K and bolt-casing E, all arranged substantially as and for the purpose described.

W. A. ROBINSON.
